US00D754174S

(12) **United States Design Patent**
Kim

(10) **Patent No.:** **US D754,174 S**
(45) **Date of Patent:** **** Apr. 19, 2016**

(54) **DISPLAY SCREEN OR PORTION THEREOF
WITH GRAPHICAL USER INTERFACE**

(71) Applicant: **AliphCom**, San Francisco, CA (US)

(72) Inventor: **Hyang Sook Kim**, Chicago, IL (US)

(73) Assignee: **ALIPHCOM**, San Francisco, CA (US)

(**) Term: **14 Years**

(21) Appl. No.: **29/495,384**

(22) Filed: **Jun. 30, 2014**

(51) **LOC (10) Cl.** **14-04**

(52) **U.S. Cl.** **D14/486**
USPC **D14/486**

(58) **Field of Classification Search**

USPC D14/485-495; D18/24-33;
715/700-867, 961-978
CPC G06F 3/0482; G06F 3/048-3/04897;
H04M 1/2477; H04M 1/72519-1/72561;
H04N 1/00408; A63F 13/53; A63F 2300/308

(57) **CLAIM**

The ornamental design for the display screen or portion thereof with graphical user interface, as shown and described.

DESCRIPTION

The single FIGURE is a front view of a display screen or portion thereof with graphical user interface showing my new design.

The broken line showing of the display screen or portion thereof forms no part of the claimed design.

1 Claim, 1 Drawing Sheet
